(57) CLAIM

The ornamental design for a label for a fabric product, as shown and described.

DESCRIPTION

FIG. 1 is a front plan view of a label for a fabric product, showing our new ornamental design.

FIG. 2 is a front plan view of a label for a fabric product.

FIG. 3 is a front plan view of a label for a fabric product; and, FIG. 4 is a front plan view of a label for a fabric product.

The broken line showing of environmental structure in the figures is for illustrative purposes only and forms no part of the claimed design.
